UNITED STATES PATENT OFFICE.

JOHN FOLLANSBEE, OF ALLEGHENY, PENNSYLVANIA, ASSIGNOR TO SHEET METAL SPECIALTY COMPANY, OF FOLLANSBEE, WEST VIRGINIA, A CORPORATION OF WEST VIRGINIA.

KNOCKDOWN CRATE.

No. 869,699.

Specification of Letters Patent.

Patented Oct. 29, 1907.

Application filed April 25, 1906. Serial No. 313,649.

To all whom it may concern:

Be it known that I, JOHN FOLLANSBEE, a citizen of the United States, residing at Allegheny, in the county of Allegheny and State of Pennsylvania, have invented 5 certain new and useful Improvements in Knockdown Crates; and I do hereby declare the following to be a full, clear, and exact description of the invention, such as will enable others skilled in the art to which it appertains to make and use the same.

10 My invention relates to shipping crates and has for its object the production of a light, durable knockdown packing and shipping receptacle which is designed and adapted primarily for inclosing and securely protecting the edges of roll tin and other sheet 15 metals; or in like manner protecting rolls of paper, cardboard and similar articles of merchandise in the course of transportation or in storage.

Heretofore it has been customary to ship roll tin roofing, for example, in wooden crates with both square 20 and round ends connected by several wooden strips, but such crates seldom reach their destination intact owing to the strains and wear occasioned by their weighty contents. Cylindrical sheet iron cases are also employed, but owing to their weight these add 25 materially to the cost of transportation. Various other expedients have been resorted to, but in the matter of general efficiency, lightness, compactness and durability the subject-matter of the present application is believed to be clearly distinguishable 30 from all devices of similar character as disclosed by the earlier art.

The invention will be hereinafter described and particularly pointed out in the claims following.

In the accompanying drawings which form part of 35 this application, and whereon the reference numerals indicate corresponding parts in the several views: Figure 1 is a perspective view of my invention represented as containing a roll of roofing tin. Fig. 2 is also a perspective view of one cap or end closure detached, and, Fig. 3 is a side elevation partly in section showing a fragmentary portion of a roll of metal, the end caps in position and one connecting metallic strap.

Reference being had to the drawings and numerals thereon, 1 indicates a roll of tin roofing, 2 indicates top 45 and bottom metallic caps or closures for the ends of such roll, the latter having inturned annular flanges 3, and surfaces slightly depressed as at 4. The periphery of these caps 2 is broken at intervals by circumferential slots 5 designed and adapted to receive the ends of 50 suitable tie rods or metallic straps 6 which may be made of wire, but are preferably formed of ordinary

hoop iron as shown. At a point or points intermediate of their ends the straps 6 are embossed or otherwise provided with an eye or loop 7 for the reception of a tie band 8 which may be employed to encircle the crate 55 and complete the package for shipment, this band or wire 8, however, is not essential. This being a description of my invention in its preferred form its use, as indicated by the foregoing description, is too obvious to require much explanation. The caps 2, 2, 60 placed over the ends of a roll as indicated by Fig. 1, are themselves connected or bound together by metallic straps 6, hooked into the slots 5 of one cap, passed straight through the corresponding slots 5 of the other cap, each strap being then folded upon itself and cut 65 just above the flange 3 as shown. Thus, tin roofing, or other materials of varying widths, are provided for, and the crate is readily adjusted to meet such varying requirements, there being practically no limit as to the spacing of caps 2, 2 by the present method of packing. 70 It will be noted also that the characteristics of the present crate are such that the caps 2, 2 are not merely secured together at opposite ends of a roll of tin or other material, but are adapted to be drawn together with great force and secured by a sharp bending 75 of the straps 6.

After the end caps have been secured in position as aforesaid the structure may be further reinforced by passing a wire or tie band 8 through loops 7 of the straps 6 as shown by Fig. 1, and while desirable this last provision is not essential to the satisfactory use and operation of the invention. It will be particularly noted that the surface of end caps 2 are depressed as at 4 thus providing raised spring edges or peripheral flanges which yield slightly when the caps are drawn together 80 by straps 6, the better to seat said caps upon the contents of the crate and always maintain the straps 6 under tension to guard against accidental displacement. Moreover, when used for crating roll tin, the spring qualities aforesaid effectually prevent any relative 85 twisting of caps 2 upon the ends of such rolls which would otherwise occur in crates of skeleton form. In like manner other minor changes and modifications may be made and substituted for the parts herein shown and described without departing from the spirit 90 of my invention, which, having been thus described, what I claim and desire to secure by Letters Patent is:

1. A metallic cap or closure for shipping crates having a raised spring edge, and circumferential slots in said 95 raised edge for the reception of suitable tie straps, substantially as described.

2. In a shipping crate the combination with end caps or closures each having a raised spring edge, of circumferential slots in raised edges, and tie straps engaging said slots for adjustably connecting the caps aforesaid, substantially as described.
3. In a shipping crate the combination with end caps or closures each having a raised spring edge in a plane parallel with the surface of said cap, of circumferential slots in said raised edges, metallic tie straps for engaging

said slots for adjustably connecting the caps, loops in said tie straps, and an encircling tie band passing through the loops aforesaid, substantially as described. 10

In testimony whereof I affix my signature, in presence of two subscribing witnesses.

JOHN FOLLANSBEE.
